UNITED STATES PATENT OFFICE.

JAMES HENRY LOADER, OF LONDON, ENGLAND.

MEANS FOR PROPELLING VESSELS.

SPECIFICATION forming part of Letters Patent No. 624,953, dated May 16, 1899.

Application filed December 20, 1897. Serial No. 662,679. (No model.)

To all whom it may concern:

Be it known that I, JAMES HENRY LOADER, a subject of the Queen of England, residing at London, England, have invented certain new and useful Improvements in or Relating to the Propulsion of Vessels, of which the following is a specification.

This invention relates to the propulsion of vessels of various kinds and may be carried out in the following manner: I arrange one or more tubes in or in connection with the hull of the vessel, each tube serving conveniently as a keelson and being open at each end to the water, although it may be provided with covers or valves in order to shut out the water when required. In this tube are one or more reciprocating pistons or equivalents, hereinafter termed "floats," and each adapted to turn so that when moving in one direction it substantially closes the tube and acts against the column of water within it to propel the ship and when moving in the other direction it "feathers" or turns edgewise in the tube, so as to leave a free waterway on each side of the float. The reciprocation of the floats may be effected by one or more steam-cylinders, the floats being carried upon the same or separate rods and the cylinders being arranged beside the tube or at the end of it or as found most convenient. Any convenient valve arrangement may be adopted for effecting the distribution of steam in the steam-cylinders and for reversing the movement of the pistons therein at the end of each stroke. Switch or equivalent automatic mechanism is so arranged that when it is desired to propel the vessel in one direction each float is turned to present its face aft, say, when making its propelling stroke and its edges fore and aft when making the return stroke, and vice versa to drive the vessel in the opposite direction.

The water-tube may extend for practically the whole length of the vessel or only a portion thereof, as desired, and it will be understood that I may employ a long steam-cylinder the stroke of which would equal that of the float in the water-tube, or I may operate the float by gearing or other mechanism from a steam-cylinder of short stroke. Either simple or compound engines may be employed for driving the floats.

In the accompanying drawings, which illustrate, by way of example, one mode of carrying out my invention, Figure 1 is a diagrammatic longitudinal section of a ship's hull, showing a single main tube in place therein. Fig. 2 is a transverse section on the line 2 2 of Fig. 1. Fig. 3 is a plan view of the hull, illustrating the general arrangement of motor-cylinders and their appurtenances relatively to the fore-and-aft main tube. Figs. 4, 5, and 6 are vertical sections on the line 4 4 of Fig. 3, showing the feathering-floats and feathering mechanism in the different positions they take up during the propulsion of the vessel, as hereinafter described. Fig. 7 is a transverse section on the line 7 7 of Fig. 5. Fig. 8 is a view of part of the interior of the main tube. Fig. 9 is an enlarged horizontal sectional view of the feather-operating mechanism, parts being broken away. Figs. 4, 5, and 6 are drawn to a larger scale than Figs. 1, 2, and 3, and Figs. 7 and 8 are drawn to a still larger scale.

A is the main tube, which lies fore and aft in the ship, or, if desired, there may be two such tubes parallel with each other on opposite sides of the keel, so as to get twin propelling mechanism. Only one tube, however, is employed in the examples illustrated.

B are sluice-valves, one at each end of the main tube, in order that it may be closed to access of the sea, if necessary. Ordinarily, however, the sluice-valves are open, and the tube affords a waterway through the ship from one end to the other.

A' is a cover, removable to allow the interior of the tube to be inspected from inboard.

C C' are the motor-cylinders, disposed within the ship at opposite sides of the tube A, one forward and the other aft.

D D' are the valve-chests of the cylinders C C', respectively. These valve-chests are supplied with steam or other motive fluid from any suitable source and are fitted with valves capable of being operated by tappet or other mechanism forming no part of the present invention.

The cylinder C, the float operated by it, and the feathering-gear and other appurtenances of both will now be described. The description thereof will serve also as a description of the similar parts, including the float H⁴, simi-

larly arranged to coöperate with the cylinder C', which will then not need to be particularly described. Within the cylinder C is a piston with two piston-rods E E' extending through 5 stuffing-boxes F on the cylinder-cover.

G is a long closed water-tight casing bolted onto the side of the main tube A in line with the cylinder C to receive the piston-rod E, which passes into it through a stuffing-box G'.

- 10 For the casing G, I may substitute a cover-plate bolted to guides, between which the piston-rod E is situated. The other piston-rod E' of each cylinder is connected to the outside cross-heads N or N', which latter are connected to each other in the manner hereinafter described. Within the water-tight casing the wall of the main cylinder A, to which the casing G is bolted, is slotted fore and aft, and through this slot extends the cross-head E², 15 constituting a connection between a feathering-float H, which is to be reciprocated in the tube, and that one of the piston-rods E by which the float H is driven. The float H is pivoted to the cross-head E² on a long pin H', carried by the latter, so as to be able to rotate about a horizontal axis extending transversely across the main tube A. Thus it will be seen that when the piston-rod E is reciprocated it causes in the present example the 20 feathering-float to travel backward and forward in the tube A for nearly half the length of the latter. The switch device by which the float H is caused to feather—that is to say, to rotate at the beginning and end of its reciprocation—will now be described. Upon 25 one side of the float two rollers H² H³ are journaled at points approximately equidistant from the pin H' or axis of rotation of the float. On the inside of the main tube A are devices 30 which act upon these rollers to produce the required feathering action. In the present instance cam-plates I and J, with their acting surfaces I' J' horizontal and I² J² inclined upward and toward each other, are fixed inside 35 the tube A at the ends of the path of the float H. Between and below these cams and also inside the tube is a bar K, held upon a pivot L and having ends K' K², beveled, as shown, in approximate correspondence with the bevel of the inclined faces I² J² of the cams I J. This bar K is the switch and, together with its companion bars at the other end of the tube, is connected 40 with an adjusting-lever K³, by which it is adjustable on the pivot L, so that it will bear with 45 one end K² on the cam-face J², leaving a clear passage-way between the end K' and cam-face I², as in Fig. 4, or reversely, so that it bears with the end K' against the cam-face I², leaving a clear passage-way between the end K² 50 and the cam-surface J², as in Fig. 6. The adjusting device for the bar K is elastic or is otherwise constructed so as to normally retain the bar in either position of inclination to which it may have been adjusted, while permitting it to yield momentarily for purposes 55 hereinafter explained. For instance, the le-

ver K³ may be held after adjustment by a spring instead of being rigidly locked.

Let it be assumed for the sake of explanation that the bar K has been adjusted in the position indicated at the left-hand end of Fig. 4 and that the float H is in the position indicated in full lines in that figure, being about to move to the left. In the position in which it is at present shown both rollers H² H³ upon it bear against the horizontal portion of the cam J, so that the float can only move forward edgewise. As it moves from under the cam J it travels along the under side of the bar K, which by acting on the rollers H² H³ 80 keeps the float horizontal in the same manner as the cam J, and after passing from under the bar K it is maintained horizontal by the other cam I, arriving at the end of its stroke in the position at which it is indicated in dotted lines at the left hand of Fig. 4. On the return stroke of the float the roller H³ meets with the inclined upper edge of the end K' of the bar K, which causes that roller to rise and the float to turn, like the float H⁴ in Fig. 6, 90 about its transverse axis and lie across the tube in a vertical plane, as at X, Fig. 4, forcing a column of water therethrough in the direction of the arrow until the float in its movement brings the roller H³ against the inclined face J² of the cam J, which retards it 95 while the axis of the float travels on. Thus the float is brought once more into the feathering position from which it started. The bar L yields to allow the roller H³ to force its way 100 between it and the cam J while the float turns, as described, from the propelling to the feathering position.

The float operates somewhat in the manner of an oar, proceeding one way along the tube 105 in a vertical position and returning edgewise, and if it be desired to reverse the direction in which the ship is propelled it is necessary merely to tilt the bar K from the position in which it is shown in Fig. 4 into the position 110 in which it is shown in Fig. 6, under which circumstances the stroke from right to left of the drawings will be the propelling stroke, thrusting a column of water along the tube A in the direction indicated by the arrow, and the stroke from left to right will be the feathering stroke—that is to say, the conditions 115 will be the converse of those which existed in the preceding example. The engines therefore need not be reversed when the action of 120 the floats is to be reversed.

In Fig. 5 the bar K is supposed to have been adjusted as in Fig. 6 below it, but is shown as yielding to allow the two rollers H² H³ to pass between its end K² and the bar M. 125 A bar M with beveled ends is fixed to the side of the tube A below each bar K in order that while one of the rollers on each float travels above the bar K during the propelling stroke the other roller passing, as it does, below the 130 bar M will prevent the float from being "feathered" until the end of the propelling stroke.

As aforesaid, there are two steam-cylinders C C', disposed toward opposite ends of the main tube A, the float H being operated by mechanism under the control of the cylinder 5 C and a similar float H⁴ being operated by the cylinder C'. The feathering devices and the arrangements for connecting the steam-piston with the float H⁴ are similar to those hereinbefore described with reference to float 10 H and, as aforesaid, need not be particularly described.

To prevent the floats from turning to feather, except at the ends of their strokes, I may provide within the tube A at the side opposite 15 to the bars K and M such a device as is illustrated in Fig. 8, wherein the sides of the tube A are formed as guide-bars H⁵, having a groove H⁶ between them, in which fits a rectangular or other projection Q' on that float. The 20 groove is widened at the ends H⁶ H⁷, and when the float arrives opposite those widened portions it can be turned; but when the float is opposite the narrow portions of the groove it can only be horizontal or vertical, because the 25 projection Q' will not enter the groove H⁶ except the float is in one of those two positions.

In order that easy and continuous propelling action may be obtained, I preferably employ two floats, such as H H⁴ in the examples 30 illustrated, and these two floats are so arranged and connected that, for instance, while one moves aft making its propelling stroke, the other is moving forward and making a feathering stroke, the last-named float 35 will in turn make its propelling stroke while the first-named float makes a feathering stroke, and so on. To insure the retention of the two floats in their proper relative positions for this alternate mode of action, the 40 piston-rods of the two cylinders C C' are outside the casings G and are each provided with cross-heads N N', respectively, and these cross-heads are connected to each other by

chains O and rods P, as shown, the equivalent of an endless chain. The chains O pass 45 around pulleys Q, turning on fixed pivots supported at opposite ends of the tube. The cross-heads being thus connected, the power of both the cylinders is applied to effect the propelling stroke of each float, the piston of 50 one cylinder acting directly on its float and that of the other acting through the chains O and rods P.

I claim—

1. In propelling means for vessels, the combination of a water-passage extending longitudinally of the vessel at the bottom thereof, and open at both ends to permit water to flow therethrough from one end to the other, a pivoted float within the passage, means for reciprocating the float, and switches within the water-passage engaged by the float, said switches being adapted to turn the float upon its pivot, at the terminals of its movement, substantially as described. 55

2. In propelling means for vessels, the combination of a water-passage extending longitudinally of the vessel at the bottom thereof and open at both ends to permit the flow of water therethrough, a pivoted float within 70 the passage, means for reciprocating the float, switches within the passage engaged by the float, said switches comprising shifting members and being adapted to turn the float upon its pivot at the terminals of its movement, 75 and means for positively actuating the shifting members of the switches, substantially as described.

In witness whereof I have hereto set my hand in the presence of the two subscribing 80 witnesses.

JAMES HENRY LOADER.
